UNITED STATES PATENT OFFICE

JESSE C. MOORE, OF INDIANAPOLIS, INDIANA, ASSIGNOR TO COLUMBIA SCHOOL SUPPLY COMPANY, OF INDIANAPOLIS, INDIANA, A CORPORATION

UNIVERSAL FOLDING CHAIR

Application filed April 7, 1930. Serial No. 442,075.

This invention relates to a so-called all metal collapsible chair.

The chief object of the invention is to produce a relatively indestructible chair suitable for schools, lecture rooms and the like, wherein all parts of the chair are preferably of metal, except the table or tablet upon which the student may write, which table or tablet is of the arm rest type.

10 The chief feature of the invention consists in the formation of a chair of the aforesaid character entirely of metal, with the exception of the table or tablet specified.

Another feature of the invention consists 15 in alternate dual positioning of the tablet when the chair is collapsed.

The full nature of the invention will be understood from the accompanying drawing and the following description and claims:

20 In the drawing Fig. 1 is a perspective view of a metal chair embodying the invention.

Fig. 2 is a front elevational view of the chair collapsed and with the tablet in upwardly extended position.

25 Fig. 3 is a similar view of the chair collapsed and with the tablet in the lower depending position.

In the drawing 10 indicates a tubular leg portion, 11 a connecting portion, the same 30 forming a tubular inverted U-shaped frame member. The bottom ends of the U-shaped frame or arms are preferably provided with feet in the form of metal caps or the like, the same being indicated by the numeral 12.

35 Said caps may, however, be of the cushion type, should silencing of chair movement while in use be desired.

The chair is of the folding type. The support for the seat includes a pair of tubular legs 13, the bearing ends of which are similarly provided with caps 14 and the upper ends of which support a pivot forming bearing member 15 which supports a pivot 16, in turn pivotally connected to an offset strip 17.

40 The other end of the strip is pivotally supported as at 18 on the depending side 19 of the chair seat which includes the perforated central load sustaining portion 20 defined by a border portion 21, the perforated portion 20 being depressed as shown relative to the

border portion. The seat apertures are indicated by the numeral 22 and form a ventilated structure similar to a cane seat. The seat flange 19 is extended along the forward edge as at 23 and a back flange 24 is likewise provided to prevent cutting of the hands in the opening and closing movement of the chair. The seat adjacent each rear corner as at 124, is provided with an edge conforming embossment which serves as a reinforcement. 55 The seat through the instrumentality of the flanges 19 is pivotally supported as at 25 by the U-shaped frame. 60

The two legs 13 are connected in spaced relation by the cross member construction 26 and said legs are pivotally supported by a cross member portion 27 secured to the U-shaped frame as at 28 and said leg construction is maintained in spaced relation, relative to the frame construction, by the 65 spacing sleeves 29 coaxial with the construction 27 and 28.

The chair is not provided with a complete back but merely a shoulder rest and the same includes a plate which is dished at its midportion. The free edge is indicated at 30, and the bottom edge adjacent thereto is turned rearwardly and the latter curled as at 31 to prevent cutting of the hands. The upper and outer portions of the shoulder rest 70 75 80 85 90 95 100 31 are turned outwardly as at 32 and are turned to conform to the curvature of the midportion of the U-shaped frame and such conforming flange 32 is spot welded or otherwise suitably secured to the midportion of the frame without danger of hand cutting projecting portions. The shoulder portion is ornamented and reinforced by including the centrally formed embossment 33 which extends forwardly from the border portion.

The tablet construction includes an L or angle shaped wooden member 40 which has secured as at 42 along its bottom face an angle iron 41 and in spaced relation therewith is an angular clip 43. A U-shaped member 44 is 85 pivotally supported at each end as at 45.

Integral therewith is a depending stem 46 which is tubular and which is provided with an elongated slot 47. Slidably supported in said tube is a rod 48. A set screw 49 adjust-

ably positions the tablet at the desired height for writing purposes by locking rod and tube together. Screw 49 also serves as a guide and prevents complete separation.

5 The rod 48 has an inwardly and angularly extending end 50 which passes through the opening 51 in the depending flange 19 of the seat. A U-shaped strap 52 having arms 53 is suitably spot welded, or otherwise secured, 10 to the under face of the seat adjacent the forward portion and the angular end 50 is rotatably mounted therein and retained against longitudinal displacement through the washer 54 and cotter key 55.

15 The rearward edge or arm rest portion of the tablet through the instrumentality of a bracket 60 suitably secured as at 61, pivotally supports said tablet as at 62, the anchorage being maintained by the nut 63.

20 When fully collapsed, it will be noted that the leg portions lie substantially in the plane of the seat and lie in the gap formed between the end of flange 19 and the adjacent end of flange 24. The link support for the legs upon 25 the seat permits of this relatively flat collapsible positioning. When it is desired to collapse the chair, the conformation of the tablet is such that when it is in extended position and the chair collapsed, it will conform to the U-shaped frame work, see Fig. 2. Likewise, the conformation is such that in the collapsing positioning, when the tablet is to be 30 positioned downwardly, the same may be accomplished by loosening the clamping screw construction 49 and permitting the 35 two telescopic members to slide one relative to the other, as noted. This positioning of the tablet is shown in Fig. 3.

It will be apparent from the foregoing that 40 standard metal structures are employed. The seat is a sheet metal stamping, the legs and frame are tubular members, the former being substantially straight, and the back being a single member fashioned in U-shaped formation. The tablet, of course, is of the conventional construction and the reinforcement for 45 the arm portion is the angle iron which simultaneously serves as the pivotal support.

The invention claimed is:

- 50 1. In a chair, the combination with a back frame and a seat pivoted thereto so as to fold up, of an arm rest pivoted at its rear end to said frame, and a support for the arm rest consisting of two telescoping members, one of said members pivoted to the front end of the arm rest and the other member pivoted to the front of the seat, whereby the arm rest may be folded either upward or downward against the folded frame and seat.
- 55 2. In a chair, the combination with a back frame and a seat pivoted thereto so as to fold up, of an arm rest pivoted at its rear end to said frame, a support for the arm rest consisting of two telescoping members, one member pivoted to the front end of the arm

rest and the other to the front of the seat, whereby the arm rest will fold either upward or downward against the folded frame and seat, and a set screw in said telescoping members for locking them when the chair is in condition for use.

3. A folding chair having a seat, a back frame to which the rear end of the seat is pivoted, legs flexibly connected with the front end of the seat to support it in a position for use and having between their ends a fulcrumed connection with said back frame whereby the seat and frame may be folded together, a combined arm rest and front tablet pivoted at its rear end to the side of the back frame, two telescoping members for supporting the arm rest and tablet, one of said members being pivoted to the front end of the arm rest and the other member beside the seat and pivoted to its front end, and a set screw for locking the telescoping members in adjusted position when the chair is in use, whereby the arm rest and tablet may be folded either up or down against the frame of the chair.

4. A folding chair having a seat, a back frame to which the rear end of the seat is pivoted, legs flexibly connected with the front end of the seat when supported in a position for use and having between their ends a fulcrumed connection with said back frame whereby the seat and frame may be folded together, a combined arm rest and front tablet pivoted at its rear end to the side of the back frame, two telescoping members for supporting the arm rest and tablet, one of said members being pivoted to the front end of the arm rest and the other member beside the seat and pivoted to its front end, and a set screw for locking the telescoping members in adjusted position when the chair is in use, said seat being so mounted that when folded upward the pivotal connection of it and the telescoping member is in the same plane as the pivotal connection between the arm rest and the back frame of the chair, whereby said telescoping members if not locked will permit the arm rest and tablet to be folded either up or down against the frame of the chair.

In witness whereof, I have hereunto affixed my signature.

JESSE C. MOORE.
